ATTORNEY

UNITED STATES PATENT OFFICE.

EDMUND L. ZALINSKI, OF THE UNITED STATES ARMY.

MANUFACTURE OF IMITATION-BULLION CAP-ORNAMENTS.

SPECIFICATION forming part of Letters Patent No. 267,816; dated November 21, 1882.

Application filed August 15, 1881. (No model.)

To all whom it may concern:

Be it known that I, EDMUND L. ZALINSKI, a citizen of the United States of America, United States Army, have invented certain new and useful Improvements in Making Imitation-Bullion Ornaments and Insignia; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to imitation-bullion ornaments for caps, shoulder-straps, badges, and the like, and the nature thereof will be fully hereinafter set forth.

Figure 1 is a face view of a cross-cannon constructed according to my invention on a fabric base. Fig. 2 is a central transverse section; Fig. 3, a back view of ornament and fastenings; and Fig. 4, a partial section on line *xx*.

25 Heretofore the finer class of ornaments for officers' wear, society, and other insignia—as crossed cannon, bugles, &c., for caps, shoulder-straps, &c.—have been made of what is known as "bullion," or "gold lace," having a film 30 of gold on a textile foundation. This is frail, and soon becomes shabby from brushing. Ornaments of this character have also been cast in metal, and a cheaper class are struck up from thin sheet metal; but these all have a 35 cheap and unsatisfactory appearance.

To carry out my intention, I take a bullion ornament as a pattern—as, for example, a cross-cannon—and from this secure a casting in brass or other suitable metal. This casting, while 40 having a general resemblance to the original, is lacking in the perfection of details. It is therefore chased and engraved by a skillful engraver, so as to perfect the resemblance to the original. This brass casting is made for 45 the reason that bullion is not hard enough to form a perfect mold, and the plastic material ordinarily used in making molds for electro-deposition will pass in between the threads of the bullion, thereby producing imperfections 50 in the mold when the pattern is withdrawn. From this mold is made by embedding in wax, plaster, or other plastic material. In this mold I make an electro-deposit of gold, as at 1, or other metal, in the usual manner of electro-

plating. The deposit of gold being made first 55 directly in the prepared matrix gives a more sharply-defined copy of the details of the ornament. I back up the gold with nickel, as at 2, Fig. 4, by the usual electroplate process. The object of this is to give a harder backing to 60 the original gold or silver deposit than would be given by copper or other soft baster metal, gold or silver electro-depositions being more or less permeable to atmospheric influences, and nickle being less subject to oxidation by 65 these than copper or other base metal, the ornament will retain its primitive brightness longer, not being so readily tarnished or "deadened" in its coloring. The nickel may be again backed by copper or other baster metal, to further strengthen the ornament. 70

In the drawings, I have shown, in Fig. 1, a face view, and in Fig. 2, a transverse section, of cross-cannon ornament made according to my invention. At the intersection of the cannon a depressed space is left to receive a letter or figure, and I fit therein a small disk of metal which may be covered with cloth, like a button-mold. A metallic letter or figure, *c*, (letter or device,) is applied above this fabric, having pins 80 at its back, which extend through the cloth, disk, and plate. The parts are secured to each other by bending the pins or attaching a screw-washer. The cross-cannon or ornament may be attached to the cap or other garment by 85 screw-washers or other device, and corresponding pins, as shown in Figs. 2 and 3.

I claim—

1. The method herein described for producing cap-ornaments in imitation of bullion, &c., 90 which consists in making a solid metallic copy from a bullion ornament, as described, perfecting the same by chasing, again making a mold and electro-depositing a fac-simile thereof in said mold.

2. The method of producing ornaments heretofore described, which consists in making a mold indirectly from a bullion pattern, substantially electro-depositing a film of gold or silver therein, backing the same with an electro-deposit of nickel, and this again with a baster metal. 95 100

In testimony whereof I affix my signature in presence of two witnesses.

EDMUND L. ZALINSKI.
